UNITED STATES PATENT OFFICE.

SYLVESTER MARSHALL, OF ATHENS, OHIO.

GRADING OR SEPARATING MACHINE.

1,399,022.

Specification of Letters Patent.

Patented Dec. 6, 1921.

Application filed March 9, 1921. Serial No. 451,057.

To all whom it may concern:

Be it known that I, SYLVESTER MARSHALL, a citizen of the United States, residing at Athens, in the county of Athens and State 5 of Ohio, have invented certain new and useful Improvements in Grading or Separating Machines, of which the following is a specification.

My invention relates to grading or separating machines and is designed as an improvement upon the machines shown in Letters Patent issued to me as follows: 1,198,395, September 12, 1916; 1,228,800, June 15, 1917, and 1,341,571, May 25, 1920.

The object of the invention is to provide a machine in which a series of oppositely inclined screens are mounted rigidly in a laterally rocking box or cradle, the uppermost screen discharging at its lower end upon the 10 screen next below and the lowermost screen discharging at its lower end through an outlet in the adjacent end of the box or cradle and there being an imperforate plate or partition under every screen and discharging laterally through outlets in one 15 longitudinal side of the box or cradle; also to provide means for centrally suspending the box or cradle and screens longitudinally within an outer supporting frame and mechanism whereby the said box or cradle may be 20 rocked laterally in opposite directions upon its suspension means until said screens are brought to an angle of about 45° for winter wheat and a steeper angle for spring wheat; also to provide a fan above the screen box 25 or cradle and operatively connected with the said box or cradle-rocking mechanism for actuation thereby; also to provide certain novel details of construction as will herein- 30 after be described and specifically pointed out in the claims.

These objects I accomplish by the mechanism shown in the accompanying drawings, in which:

Figure 1 is a side elevation of my improved machine.

Fig. 2 is an end elevation.

Fig. 3 is a central longitudinal section through the laterally rocking screen box 50 or cradle, and

Fig. 4 is a transverse vertical section through Fig. 3.

A suitable upright frame 1 is provided within which is suspended a rectangular 55 screen-carrying box or cradle 4. The box or cradle 4 is provided with end trunnions 5

extending mounted in bearings 6 secured to the ends of the upright frame 1 so that the screen-carrying box or cradle 4 may be rocked laterally in opposite directions. To 60 effect this rocking action one end of the screen-carrying box or cradle 4 is provided at one end with an operating arm 7 having a plurality of apertures to one of which is connected an operating rod 8 engaging an eccentric pin 10 mounted on a disk 9 driven by a sprocket 11 connected to a second sprocket 12 by a sprocket chain 13. The sprocket 12 is mounted on a drive shaft 14 having a sprocket 15, which in turn is connected to a sprocket 16 by a sprocket chain 17. The sprocket 16 is mounted on the shaft 18 of a fan blower 19 mounted upon the top of the main frame 1. The shaft 14 is driven by a drive pulley 21 mounted thereon. 75

The shaft of the fan blower 19 is connected to a longitudinally reciprocating frame 22 in front of the blast trunk 23 of the casting 25 mounted on top of the frame 1. This frame 22 is suspended by links 26 and is 80 connected by a pitman 26' with an eccentric pin 27 on the sprocket wheel 16 that rotates the fan shaft 18. Within the frame 22 is placed an upper forwardly and downwardly inclined chaff-separating screen 27, the 85 higher end of which is next to the fan 19 and directly below the outlet of a feed hopper 28. The lower forward end of the screen 27 discharges the grain upon the upper forward end of a reversely inclined 90 lower screen 29 and the rear lower end of this screen 29 discharges through an outlet 30 upon the higher inner end of a forwardly and downwardly inclined grading screen 31. This screen 31 discharges at its lower end 95 through an opening 32 upon the higher end of a reversely inclined screen 33, which in turn discharges at its lower end through a similar opening 32 upon the upper end of a third screen 34, and this screen 34 discharges 100 at its lower end through an opening 32 upon the lowest screen 35, which in turn discharges through its outlet into a receptacle 36. Below the screens 31, 33 and 34 horizontal plates or partitions 37 are placed, 105 the ends thereof next to the openings 32 in said screens being provided with openings 39 to permit the passage therethrough of the seed grain from one screen to the other. At each longitudinal side of these partitions or plates 37 and a bottom plate 38 the sides of the screen box or cradle 4 are provided with

110

long slits or outlets 40 for the discharge of the smaller imperfect grain that falls through the meshes of the screens upon the partitions or plates. The screens and partitions are held in place by suitable grooves 21 and a panel 21' one-half the size of the side of the box is made removable to get at the interior and permit lateral removal of the middle screens when a less amount is required to be screened out to obtain perfect seed.

Each screen 31, 33, 34 and 35 is formed of an outer oblong frame 41 having its long sides inclined outwardly and downwardly from the screen material and covered with imperforate metal plates 42. A short metal plate 42' extends across one end of each screen under openings 39 to prevent wheat from falling through the screens when their slant is not at 45° angle.

These inclined side plates 42 and plate 42' prevent the seed grain from falling through the screens when they reach the end of their lowermost throw in either direction and start the grain on its travel transversely across the screens from their higher sides. As in my said patents before referred to, the mesh of the screens is larger than the greatest transverse diameter of the largest seed grain or particles of material to be graded. Therefore, in the lateral rocking motion of the inclined screens only the largest grains thereon will fail to fall through and be passed down the longitudinal incline to the screen next below and all of the smaller inferior grains will fall through the screens upon the partitions 37—38 and be discharged by the lateral throw of the box or cradle through the openings 40 in the sides thereof, where they may be caught in any suitable receptacle placed along that side of the machine. Thus while I have retained my feature of the large mesh of screen shown in said patents I have provided a machine capable of a very greatly enlarged output of selected seed grain.

The operation, briefly stated, is as follows: Grain from the hopper is fed continuously upon screens 27—29 and the chaff and the like are blown through the open front end of the frame 22; the cleaned grain to be graded falling through opening 23' down upon the high end of the uppermost grading screen in the cradle. The longitudinal inclination of the grading screen 31 causes a flow of the larger grains toward the lower end thereof to the high end of the screen next below, and so on to the outlet of the lowermost screen. In the lateral rock of the screens the grain will be rolled transversely across the screens and so progress gradually toward the outlet. Only the very largest grains will thus fail to fall through the screens and be saved for seed. All of the smaller inferior grains and any remain-

ing foreign matter will fall through the large mesh and upon the partitions or plates for discharge at the side of the machine. The object is not the ordinary winnowing and screening followed at present, but the selecting out of the most perfect grains only for seed purposes, which will, of course, result eventually in increasing the size of the grains in succeeding crops.

Of course, a better quality of grain and a corresponding increase in the price obtained therefor will follow.

What I claim is:

1. The combination with a suitable support, of a laterally rocking longitudinally inclined screen mounted on said support and discharging at its lower end; the mesh of the screen being larger than the greatest diameter of the grains to be separated or graded, a horizontal plate or partition mounted under the screen for movement therewith to receive the material which falls through the screens and discharge it at one longitudinal edge, and means for rocking said screen and connected plate or partition.

2. The combination with a suitable support, of a laterally rocking longitudinally inclined screen suspended at its ends therein and having plates along its side edges to prevent material from falling through at such points; the mesh of the screen being larger than the greatest transverse diameter of the grains to be graded or separated, and means for rocking the screen.

3. The combination with a suitable support, of a laterally rocking longitudinally inclined screen suspended at its ends therein and having its longitudinal edges inclined from the screen material outwardly and downwardly; the screen mesh being larger than the greatest diameter of the grains to be separated or graded, and means for rocking the screen laterally.

4. The combination with a suitable frame, of a box or cradle having bearings centrally of its ends for rocking movement, oppositely inclined screens mounted longitudinally of the box or cradle and discharging downwardly from their lower ends successively one upon the other; the lower end of the lowermost screen discharging at one end of the box or cradle, horizontal plates or partitions in the box or cradle between the screens; the box or cradle having longitudinal openings in one side registering with the adjacent longitudinal sides of the partitions or plates, and means for rocking the box or cradle laterally.

5. A grain separator or grader comprising a frame or support, a box or cradle suspended centrally of its ends in the ends of said frame and having grading screens and partitions to discharge at the ends and sides of the frame, respectively, a fan blower

mounted above the box or cradle and having a longitudinally extending trunk discharging at one end of the frame, oppositely inclined superposed reciprocating separating screens in front of the fan, the lower end of the lower screen discharging downwardly upon the adjacent end of the uppermost

grading screen, a driven shaft, and operative connections between said shaft and the screen box or cradle, the fan and the longitudinally reciprocating separating screens.

5 In testimony whereof I affix my signature.

SYLVESTER MARSHALL.
